United States Patent Office

Des. 228,015
Patented July 31, 1973

228,015

PENDANT

Ade Bethune, Newport, R.I., assignor to Terra-Sancta Creations, Inc., Philadelphia, Pa.

Original design application Nov. 13, 1970, Ser. No. 25,962, now Patent No. 224,599. Divided and this application Dec. 30, 1971, Ser. No. 214,507

Term of patent 14 years

Int. Cl. D11—01

U.S. Cl. D45—16 A

FIG. 1 is a front elevation of my new design for a pendant; and

FIG. 2 is a rear elevation view thereof, the side edge being of conventional thickness and unornamented.

This is a division of my design application Ser. No. D. 25,962, filed Nov. 13, 1970, and patented Aug. 8, 1972, Pat. No. D. 224,599.

I claim:

The ornamental design for a pendant, as shown and described.
